US0D1014963S

(12) United States Design Patent (10) Patent No.: US D1,014,963 S
(45) Date of Patent: * Feb. 20, 2024

(54) WALLET

(71) Applicant: MIWORLD ACCESSORIES LLC,
New York, NY (US)

(72) Inventors: Judah Uziel, New York, NY (US);
Joseph Uziel, New York, NY (US)

(73) Assignee: MIWORLD ACCESSORIES LLC,
New York, NY (US)

() Term: 15 Years

(21) Appl. No.: 29/795,201

(22) Filed: Jun. 17, 2021

(51) LOC (14) Cl. 03-01

(52) U.S. Cl.

USPC D3/247; D3/249; D14/251

(57) CLAIM

The ornamental design for a wallet, as shown and described.

DESCRIPTION

FIG. 1 is a front view of a wallet showing our design;

FIG. 2 is a left view thereof;

FIG. 3 is a right view thereof;

FIG. 4 is a rear view thereof;

FIG. 5 is a top view thereof;

FIG. 6 is a bottom view thereof;

FIG. 7 is a front perspective view thereof;

FIG. 8 is a front perspective view thereof, showing the wallet as it would appear attached to a phone case;

FIG. 9 is a front view thereof, showing the wallet as it would appear attached to a phone case and holding an object; and, FIG. 10 is a front view thereof, showing the wallet as it would appear attached to a phone case and held in a user's hand.

Throughout the figures, broken lines show environment that forms no part of the claimed design.

1 Claim, 8 Drawing Sheets
